UNITED STATES PATENT OFFICE

2,604,725

CURTAIN STRETCHER

William Jungjohann, Muscatine, Iowa

Application August 11, 1949, Serial No. 109,783

8 Claims. (Cl. 45—24)

1

This invention relates to a curtain stretcher and has for its principal object the provision of an improved foldable and adjustable stretcher, preferably of the so called pinless type.

Foldable and adjustable curtain stretchers are, of course, known, but the various types heretofore proposed have not been commercially feasible, because the complicated designs thereof are inherently costly and the price thereof to the ultimate user is ordinarily so high as to virtually eliminate them as competitors of the well known knock down pin-type stretcher. The disadvantages of the curtain stretcher last mentioned are well known to those who have been plagued by the problems of assembly and adjustment thereof in use and the difficulty involved in properly squaring the corners so that the stretching of the curtain would be acceptable.

According to the present invention, the preferred form of stretcher comprises a pair of elongated, parallel side rails interconnected by braces or links and including stabilizing means and equalizing means for maintaining perfect parallelism of the side rails through a range of adjustment sufficiently wide to accommodate the smallest and the largest curtains and like fabric articles. It is an important object of the invention to provide improved means for maintaining any selected adjustment or spacing between the side rails. The invention has for a further feature the provision of brace members which cooperate with rigid adjusting links to form triangular structures that are both light weight and appropriately rigid to space the side rails.

Other objects of the invention are to provide each of the side rails and the center bar or stabilizer as a pair of parts interconnected by hinge means, the hinge means lying on a common axis so that the stretcher frame may be folded about said axis; to provide the adjustable triangular structures or bracing means with hinges on parallel axes normal to the hinge axis of the side rails and to mount the apices of the triangular structures slidably on the center bar so that as the side rails are moved toward each other the hinges at the apices of the triangular structures move toward the hinge axis of the side rails, whereby when the frame is folded the aforesaid hinge axes will substantially intersect, enabling the entire frame to be folded into a compact structure that will stand by itself and one that may be easily carried and stored.

Still further objects of the invention reside in improved means forming a wire or rod on each side rail so that the curtain may be supported by improved curtain clamps. The wire or rod structure is made up of a plurality of separate elements secured to the side rail with lengthwise portions thereof in longitudinal alinement and running lengthwise of the side rail, thus avoid-

2

ing the use of a single wire which is apt to stretch and yield unless supported at spaced intervals by supports that are costly and that often result in damage to curtains being stretched. The improved curtain clamps are preferably in the form of modified spring-type clothespins, the modification residing in secondary notches in the clamp jaws for releasably retaining the clamp on the wire, thus avoiding prior known designs in which the wire passes permanently through the coiled torsion spring of the clamp.

The foregoing and other important objects and desirable features inherent in and encompassed by the invention will become apparent as a complete disclosure is made of a preferred embodiment of the invention in the following detailed description and accompanying sheets of drawings in which:

Figure 1 is a plan view of the stretcher frame.

Figure 2 is a side elevational view of the stretcher frame, showing the frame supported in an inclined position by supporting legs.

Figure 3 is an enlarged fragmentary perspective view showing the joint provided to achieve foldability of one of the supporting legs.

Figure 4 is a transverse sectional view taken substantially on the line 4—4 of, and drawn to the same scale as, Figure 1.

Figure 5 is a fragmentary perspective view, partly in section, as viewed generally along the line 5—5 of Figure 1.

Figure 6 is an enlarged fragmentary perspective view, partly in section, as viewed generally along the line 6—6 of Figure 1.

Figure 7 is a fragmentary sectional view taken on the line 7—7 of, and drawn to the same scale as, Figure 6.

Figure 8 is a perspective view of the intermediate portions of the frame structure, showing the relationship of the hinges as the frame parts approach a completely folded position.

Figure 9 is a fragmentary perspective view, partly in section, as seen generally along the line 9—9 of Figure 1.

Figure 10 is a fragmentary sectional view showing a side rail, with one of the wire or rod elements mounted thereon, and a curtain clamp carried by the wire element.

Figure 11 is a view of the curtain clamp illustrating the manner in which it may be removed from the wire.

Figure 12 is a fragmentary sectional view taken substantially along the line 12—12 of Figure 10.

Figure 13 is a fragmentary perspective view showing one of the end bars passed through the hem of a curtain.

The frame comprises a pair of side rails 15 and 16 and a center or stabilizer bar 17. Adjustable spacing between the side rails is maintained by a pair of triangular bracing structures, desig-

nated generally by the numerals 18 and 19, which cooperate with the center bar 17. The center bar carries a pair of slides 20 and 21 for the structures 18 and 19 respectively.

The slide 20 is preferably in the form of a metal clip which receives the center bar and which has fixed thereto an upstanding pivot pin 22 (Figures 6 and 7). The bracing structure 18 comprises a pair of brace members 23 and 24 that are hingedly interconnected by the pivot pin 22 by means of a hinge 25.

The braces 23 and 24 diverge toward one pair of end portions of the side rails 15 and 16 and are respectively pivotally connected to the rails by brackets 26 and 27 and pivots 28 and 29.

The side rails 15 and 16 and the center bar 17 lie substantially in the same plane (Figure 4). The pivots 22, 28 and 29 are parallel to each other and normal or perpendicular to the general plane of the side rails and center bar.

The other triangular structure 19 is similar to the structure 18 and comprises a pair of braces 30 and 31 having end portions interconnected by a hinge 32 and pivot pin 33 to the slide 21, the pin 33 being fixed to the slide in the same manner as the pin 22 is fixed to the slide 20. The braces 30 and 31 diverge to the opposite end portions of the side rails 15 and 16 and are connected to the side rail portions respectively by brackets 34 and 35 and pivots 36 and 37.

It will be seen from the description thus far that the spacing between the side rails may be readily varied. As the side rails move toward each other the slides 20 and 21 will move lengthwise of the center bar 17 toward each other, or toward the center of the center bar; conversely, as the side rails are spread the slides 20 and 21 move away from each other lengthwise of the center bar 17. Hence, adjustment of the lateral spacing between the side rails effects variation in the angles of divergence of the braces 23-24 and 30-31. The fixation of these braces for the purpose of fixing the lateral spacing between the side rails is accomplished by a third member in each of the triangular structures 18 and 19. This member for the structure 18 comprises a rigid adjusting link 38 having one end portion bent at right angles, as at 39 (Figure 5) and fitted into a bore 40 in the brace 23. The adjusting link 38 is thus pivoted at a fixed location on the brace 23 and extends transversely across to the other brace member 24. The brace 24 carries a clamp 41 which has an apertured ear 42 in which the opposite end of the link 38 is received, this end having a portion 43 bent at right angles to the link for that purpose. The clamp is adjustable lengthwise of the brace 24 and any selected position thereof may be secured by tightening securing means including a bolt 44 and wingnut 45. The brace 24 is provided with longitudinally spaced graduations and numerals to facilitate setting of the clamp 41 on the brace and consequently to enable the user to determine the spacing between the side rails (see Figures 1 and 5).

The third member that makes up the triangular structure 19 likewise comprises a rigid adjusting link 46 having one end pivoted at 47 to the brace 31 and its other end carried by an adjustable clamp 48 similar to the clamp 41. The brace 30 is graduated like the brace 24.

In order to provide stability for the frame and to equalize the movement of the braces 30 and 31 as the side rails are being adjusted, the structure 19 includes equalizing means comprising a slide 48 and links 49 and 50. The slide 48 is

carried by and is slidable lengthwise of the center bar 17. The link 49 is pivotally interconnected between the brace 30 and the slide 48; and the link 50 is pivotally interconnected between the brace 31 and the slide 48. Similar equalizing means could be provided for the structure 18 but in the interest of economy is omitted.

It will be seen from the description thus far that each of the triangular structures 18 and 19 may be rigidified by its rigid adjusting link and the spacing between the side rails may be secured on the basis of adjustment of the links 38 and 46 respectively along the braces 24 and 30. The center bar 17 ties the two triangular structures 15 together so that the frame cannot "diamond"; that is, so that the side rails 15 and 16 cannot shift lengthwise in opposite directions relative to each other.

The entire frame structure may be compactly folded so that it may be easily carried and stored. Further, the folded frame may stand upright by itself. These results are achieved by making provision for the folding of the side rails and center bars and by tying the foldability of these elements in with the hinging of the braces 23-24 and 30-31 respectively about the axes of their pivots 22 and 33.

The side rail 15 comprises two parts 15a and 15b; the side rail 16 comprises two parts 16a and 16b; and the center bar comprises two parts 17a and 17b. The side rail parts 15a and 15b are preferably of equal length and their proximate ends are hingedly interconnected by a hinge 51, the axis of which is transverse to the side rails or parallel to the general plane of the frame elements. The proximate ends of the side rail parts 15a and 15b are preferably provided with reinforcing blocks 52 and 53 respectively. The other side rail parts 16a and 16b are similarly interconnected by a hinge 54 and the rail parts respectively have reinforcing blocks 55 and 56. The hinges 51 and 54 are coaxial.

The center rail parts 17a and 17b have their proximate inner ends interconnected by a hinge 57 which comprises a pair of hinge leaves 58 and 59 and a hinge pin 60 (Figure 8). The axis of the hinge 57 is coaxial with the axis of the hinges 51 and 54. Hence, the entire frame structure may be folded about the general transverse axis indicated by the line A-A in Figures 1 and 8.

Inasmuch as the center bar 17 slidably carries the slides 20 and 21, provision must be made for centering the bar so that the axis of the hinge 57 will always be in alignment when the frame is collapsed or folded. As will best be seen in Figure 8, this result is achieved by arranging the slides 20 and 21 so that they will respectively engage the hinge leaves 59 and 58 as the slides approach each other when the side rails 15 and 16 are moved completely toward each other. The slides 20 and 21 and hinge leaves 59 and 58 thus constitute cooperating elements respectively on the center bar parts and the triangular structures 18 and 19 for maintaining alignment of the axis of the hinge 57 with the axis of the hinges 51 and 54. It will thus be seen that when the frame is completely folded the pivot pins 22 and 33 will lie substantially on a common axis which is normal to and which substantially intersects the axis A-A. Opposite ends of the center bar 17 are provided respectively with stops 20a and 48a which are respectively engageable with the slides 20 and 48 so that the center bar will not slip out of the slides.

The frame is ordinarily used in the position

shown in Figure 2, in which it is supported at an angle by means of a pair of legs or props 61 and 62 (see also Figure 1). The construction of both legs is the same and the description of the leg 61 will suffice for both. This leg comprises a pair of sections 61a and 61b having their proximate ends pivotally interconnected by a bolt 63 and wingnut 64 (Figure 3) so that the part or section 61b may be folded upwardly to lie alongside the part 61a. The latter part is pivotally connected to the side rail part 16a by means of a bolt and wingnut 65 so that the folded leg may be folded up alongside the side rail. The wingnut 65 may be tightened to maintain the leg in either its supporting or folded position. The wingnut 64 may be likewise tightened for either of these purposes. As best shown in Figure 3, the lower leg part 61b has fixed thereto an abutment or stop 66 for engagement with the upper leg part 61a when the leg is in its supporting position. A chain 67 is interconnected between the side rail part 16a and the leg 61 for obvious purposes.

When the frame is in any of its adjusted or extended positions a curtain may be stretched thereon by means including a pair of wire or rod structures 68 and 69, mounted respectively on the side rails 15 and 16 and a pair of end or hem bars 70 and 71 carried respectively at opposite ends of the frame.

The upper or right-hand ends of the side rails respectively carry supporting blocks 72 and 73. Since both blocks are the same only the block 73 will be described. As best seen in Figure 2 the block 73 is provided with a pair of upper and lower slots 74 and 75, in each of which a hem bar may be mounted, thus enabling the frame to carry a pair of curtains at the same time. Figure 2 shows the hem bar 71 carried in the lower slot 75.

The opposite ends of the side rails respectively carry a pair of adjustable supporting blocks 76 and 77. As best seen in Figure 2, the block 77 is provided with upper and lower slots 78 and 79 for receiving a pair of hem bars, the spacing of the slots corresponding with the spacing of the slots in the upper blocks 72 and 73. The other adjustable block 76, is, of course, provided with a pair of corresponding slots (not shown). Figure 9 shows the manner in which the block 76 is adjustably carried by the side rail 15 and supporting wire or rod structure 68. This block is apertured at 80 to receive a bolt 81 which has a hooked end 82. The hooked end receives the wire or rod structure and the opposite end of the bolt is threaded and receives a wingnut 83. The other block 77 is similarly carried on the side rail 16 and wire or rod structure 69, having a hooked bolt 84 and wingnut 85. Thus, the blocks 76 may be selectively fixed in any adjusted position to accommodate curtains of different lengths. Figure 13 shows a curtain at C, having a hem H through which the hem bar 18 (71) may be passed. The hem bars are made quite long so that end portions thereof may be readily received in the supporting blocks 72-73 and 76-77 with the edges of the curtain lying respectively along the wire or rod structures 68 and 69.

It is a feature of the invention to provide improved wire or rod structures for supporting the edges of the curtain. The wire or rod structures 68 and 69 are made up of a plurality of separate or individual wire or rod elements 86. Each of these elements is in the form of a U having a relatively long bight 87 and a pair of legs 88 and 89 depending therefrom at right angles thereto.

The elements 86 are arranged along the side rail so that the bights 87 are in longitudinal alignment and parallel to the upper edge of the side rail, being slightly spaced above said edge. Each of the legs 88, 89 has its free end portion bent at right angles to the leg as at 90 (Figure 10). These portions 90 are driven into or embedded in the side rail and thus serve as means to mount the elements on the side rail. The leg 88 of one element is closely proximate to or lies alongside the leg 89 of a neighboring element and the two proximate legs so arranged are further secured to the side rail by additional securing means including a staple or strap member 91 which embraces the two legs and which is driven into the side rail (Figures 9, 10 and 12).

The elements 86 are preferably about twelve inches long and being thus relatively short are individually rigid, yet are so arranged that the bight portions 87 form in effect a substantially continuous wire or rod along the respective side rail. It will be noted from an examination of Figures 1 and 2 that the elements 86 proximate to the hinges 51, 54 are spaced apart sufficiently to accommodate the hinges.

A further feature of the invention resides in improved means for mounting the curtain on the wire or rod structures 68 and 69. This means comprises a plurality of preferably identical curtain clamps, each of which may take the form of a modified clothespin of the spring type. Such clamp is shown in Figures 10 and 11.

This clamp comprises a pair of complementary parts 92 and 93. These parts respectively have jaw portions 94, 95 and handle portions 96, 97. A coiled torsion spring 98 has extending legs 99 and 100 respectively engaging the jaws 94 and 95 to maintain the jaws in closed or clamping position. The important modification of the spring-type clothespin or curtain clamp resides in the provision of a pair of complementary notches 101 and 102 respectively in the parts 92 and 93 intermediate the jaws and the torsion spring 98. Each notch is so dimensioned and shaped as to relatively tightly fit substantially one-half of the periphery of the bight portion 87 of a wire or rod element 86, the purpose being to retain the curtain clamp on the wire against displacement both laterally and lengthwise of the wire when the jaws are closed and even though a curtain is not engaged between the jaws. The torsion spring 98 is outwardly of the wire and the jaws are inwardly of the wire, when the clamp is mounted on the wire, thus distinguishing from some prior structures in which the clamp is permanently attached to the wire because the wire passes through the torsion spring. According to the present invention the clamps are removable from the wire or rod structure and yet may be mounted and retained thereon by means of the notches 101 and 102 without depending on the curtain for support.

The primary characteristic of the curtain stretcher provided according to the present invention is that it is of simple design that may be economically constructed, that may be easily handled by the user and that will readily stand hard usage. The adjustability thereof is easily accomplished and the relatively rigid interbracing of the side rails assures parallelism between the rails regardless of the spacing between the rails. The frame may be easily folded into a compact bundle for carrying and storing. The wire or rod structure 68 and 69 are of simple and rigid construction and are not likely to be distorted or otherwise damaged.

The foregoing and other features of the invention not specifically enumerated above will occur to those versed in the art, as likewise will numerous modifications and alterations of the preferred form of the invention illustrated, all of which may be achieved without departing from the spirit and scope of the invention as defined in the appended claims.

What is claimed is:

1. A curtain stretcher frame, comprising: a pair of elongated, parallel side rails, each having first and second opposite end portions; an elongated center bar between and parallel to and lying generally in the plane of the side rails; first and second longitudinally spaced apart slides mounted on and intermediate the ends of the center bar for relative lengthwise shifting; first and second pivot pins respectively fixed to the slides and extending normal to the aforesaid plane; a first pair of braces hingedly interconnected by and to the first pivot pin and diverging toward and respectively connected to the first end portions of the side rails by pivots parallel to the pivot pins; a second pair of braces hingedly interconnected by and to the second pivot pin and diverging toward and respectively connected to the second end portions of the side rails by pivots parallel to the aforesaid pivots; a first adjusting means including a rigid link pivoted at one end to one brace of the first pair on an axis parallel to the aforesaid pivots and extending transversely toward the other brace of said first pair, and means for releasably connecting the other end of the link to said other brace of the first pair at any one of a plurality of selected points spaced lengthwise along said other brace to vary and fix the angle of divergence between said braces of the first pair; and a second adjusting means similar to said first adjusting means and similarly arranged with relation to the braces of the second pair.

2. The invention defined in claim 1, further characterized in that: each of the releasable connecting means for the adjusting links comprises a clamp element, securable to said other brace in selected positions as aforesaid, and having an apertured portion for removably receiving said other end of the adjusting link.

3. The invention defined in claim 1, further characterized in that: each side rail and the center bar comprises two parts interconnected by a central hinge and the three hinges are coaxial on an axis transverse to the bar and rails and parallel to the aforesaid plane; and the spaced apart relation of the slides is such that one slide is carried on one center bar part and the other slide on the other center bar part with the center bar part between them.

4. The invention defined in claim 3, further characterized in that: the center bar parts and the slides have cooperative elements interengageable when the slides approach the center bar hinge to center or re-align said center bar hinge with the side rail hinges.

5. The invention defined in claim 4, further characterized in that: the cooperative elements comprise a portion on each slide and a portion on each half of the center bar hinge engageable with the respective slide portion.

6. The invention defined in claim 4, further characterized in that: the slides and center bar parts have second cooperative elements interengageable when the slides approach the free

ends of the center bar parts to prevent escape of either center bar part from its respective slide.

7. A curtain stretcher frame, comprising: a pair of elongated, parallel side rails, each having first and second opposite end portions; an elongated center bar between and parallel to and lying generally in the plane of the side rails; first and second longitudinally spaced apart slides mounted on and intermediate the ends of the center bar for relative lengthwise shifting; first and second pivot pins respectively fixed to the slides and extending normal to the aforesaid plane; a first pair of braces hingedly interconnected by and to the first pivot pin and diverging toward and respectively connected to the first end portions of the side rails by pivots parallel to the pivot pins; a second pair of braces hingedly interconnected by and to the second pivot pin and diverging toward and respectively connected to the second end portions of the side rails by pivots parallel to the aforesaid pivots; a first adjusting means cross-connecting the braces of the first pair to form a triangle therewith and including provision for adjusting and selectively fixing the angle of divergence between said braces; and second adjusting means cross-connecting the braces of the second pair to form a triangle therewith and including provision for adjusting and selectively fixing the angle of divergence between said second braces.

8. A curtain stretcher frame, comprising: a pair of elongated, parallel side rails, each having first and second opposite end portions; an elongated center bar between and parallel to and lying generally in the plane of the side rails; first and second longitudinally spaced apart slides mounted on and intermediate the ends of the center bar for relative lengthwise shifting; first and second pivot pins respectively fixed to the slides and extending normal to the aforesaid plane; a first pair of braces hingedly interconnected by and to the first pivot pin and diverging toward and respectively connected to the first end portions of the side rails by pivots parallel to the pivot pins; a second pair of braces hingedly interconnected by and to the second pivot pin and diverging toward and respectively connected to the second end portions of the side rails by pivots parallel to the aforesaid pivots; a first adjusting means for the first pair of braces for adjusting and selectively fixing the angle of divergence between said braces; and second adjusting means for the second pair of braces for adjusting and selectively fixing the angle of divergence between said second braces.
